UNITED STATES PATENT OFFICE.

SYLVESTER GOSS HAMER, OF WEST DECATUR, PENNSYLVANIA, ASSIGNOR OF ONE-THIRD TO JAMES W. ECKLEY, OF WEST DECATUR, PENNSYLVANIA.

BRICK-SIZING MACHINE.

Application filed April 26, 1927. Serial No. 186,729.

This invention relates to a machine designed primarily for sizing the stock used in the formation of fire brick. Where brick presses are used it is essential that the bulk 5 of the stock supplied thereto be uniform to insure the production of brick of uniform size. Various means have been provided for insuring the proper sizing of the stock but these means have heretofore been objectionable either because of the cost of operation, 10 cost of mechanism required, or of inefficiency.

It is an object of the present invention to provide a machine for use in connection with a single brick press whereby the stock, as it 15 is supplied to the machine, will be automatically sized to produce mud bricks of uniform bulk to be fed into the press.

A further object is to provide sizing mechanism utilizing a form for placing the stock 20 under pressure during the sizing operation, thereby causing surplus stock to exude at points where it can be cut off so as to leave within the form the predetermined bulk of material.

25 Another object is to provide a machine of this character adjustable so as to size bricks of different bulks.

With the foregoing and other objects in view which will appear as the description 30 proceeds, the invention resides in the combination and arrangement of parts and in the details of construction hereinafter described and claimed, it being understood that changes in the precise embodiment of the invention herein disclosed may be made within 35 the scope of what is claimed, without departing from the spirit of the invention.

In the accompanying drawings the preferred form of the invention has been shown.

40 In said drawings,

Figure 1 is a plan view of the sizing machine constituting the present invention.

Figure 2 is a side elevation thereof.

Figure 3 is a section on line 3—3, Figure 45 1.

Figure 4 is a section on line 4—4, Figure 1.

Figure 5 is a section on line 5—5, Figure 1.

50 Figure 6 is an enlarged section through a portion of the yieldable rack.

Figure 7 is a section on line 7—7, Figure 1.

55 Figure 8 is a view similar to Figure 7 showing the relative positions of the parts

immediately following the sizing and withdrawal of the bulk material.

Figure 9 is a section similar to Figures 7 and 8 showing the relative positions of the parts during the sizing of the bulk material. 60

Figure 10 is a view partly in elevation and partly in section of a portion of the cross head and adjacent structure showing the yieldable support for one end of the cross head. 65

Figure 11 is a view similar to Figure 9 showing a modified form of gate.

Referring to the figures by characters of reference A designates a double press provided with the usual feed table B. To the 70 sides of the table B are connected the side frame members 1 of the machine constituting the present invention, these frame members being connected at one end by a cross member 2 supported at a desired distance away from the table B. A feed chute 3 or the like can be mounted on the cross member 2 for the purpose of supplying stock to the machine. 75

Each of the frame members 1 is provided, 80 in its inner face near the upper or top surface, with a longitudinal groove 4 and these grooves constitute guideways for the side edges of a cut off slide 5. Secured on the side portions of this slide are reinforcing strips 6 and these strips project at one end beyond the slide and are formed with longitudinal slots 7 in which are movably mounted pitmen 8 constituting connections between the strips 6 and the mechanism of the press A. The manner of connecting the mechanism to the press constitutes, in itself, no 85 part of the present invention and, therefore, this connection has not been disclosed. It is merely necessary that the movement of the slide 5 be so timed that the sized bulk material be brought to position in the press during the proper time intervals. 90

The slide 5 has a depending transverse portion 9 slidably engaging the upper surface of the table B, thereby providing a transverse shoulder or abutment 10 for the purpose of pushing sized material along the table to the press. Secured to the slide 5 along that edge thereof remote from abutment 10 is a shearing blade 11 the cutting edge of which is in the same plane with the top surface of the slide 5. Each reinforcing strip 6 of the slide has a spring latch 12 100 projecting from one end thereof and over- 105

hanging and extending past the ends of the blade 11. Each latch has a beveled head 13 depending from its free end for the purpose hereinafter explained. A finger 14 is extended laterally from each head 13 and secured on the side members 1 at proper points to effect the operation hereinafter explained, are lifting cams 15 arranged in the paths of the respective fingers 14.

10 Secured to the frame members 1 beyond the end of the table B are standards 16 connected at their upper ends by a cross bar 17. Each standard has a longitudinal slot 18 extending transversely therethrough and 15 slidable within these slots are the ends of a cross head 19. This cross head is yieldingly supported by any suitable means. For example, a spring 20 may be arranged under each end portion of the cross head with its 20 lower end resting on an adjusting screw 21. See Figure 10. Thus the cross head will be normally in elevated position and, when moved downwardly, will place the springs under compression.

25 Guide plates 22 are mounted on the outer sides of the standards 16, the ends of these plates being adjustably connected to the standards by means of bolts 23 extending into longitudinal slots 24. Thus by loosening the bolts the guide plates can be raised or lowered relative to the standards. A switch 25 in the form of an elongated slide is mounted within each guide member and has an elongated opening 26 one end of 30 which is preferably at right angles to the upper and lower walls of the opening while the other end wall of the opening is inclined, as at 27 up to a slot 28 constituting an extension of the upper portion of the opening.

40 Extending across the opening 26 from the top to the bottom thereof and at the outer side of the switch 25 is a supporting strip 29 to which is pivotally connected a switch tongue 30. This switch tongue is so proportioned that, when supported in an intermediate position, its edges will be regularly spaced from the walls of the opening 26. Inasmuch as the tongue is pivoted at a point off center, one end portion thereof will normally rest upon the bottom wall of the opening 26 as shown in Figure 2 while the other or tapered end portion has its point 31 normally bearing upwardly against the top wall of the opening 26. Pins 32 are extended 50 from the ends of the cross head 19 and are adapted to travel in the spaces between the tiltable switch tongues 30 and the walls of the openings 26. The slots 28 are also proportioned to receive these pins. Arms 33 are 55 fixedly connected to the switch members 25 and to the strips 6 of the slide 5, these arms thus cooperating with the guide plates 22 to maintain the switch members 25 in proper positions during reciprocation with the 60 strips 6 and slide 5.

The cross head 19, in the structure illustrated, is provided with two depending flanges 34 to each of which is secured a form head 35 which can be made of a metal plate of suitable stiffness, of wood, or any other 70 desired material, the longitudinal and transverse dimensions of this head being the same as those of the sized brick. In the structure illustrated each of the form heads has an upstanding flange 36 at each end and to each of these flanges is adjustably connected one of the end plates 37 of the sizing form. These end plates can be slotted as shown at 38 to receive fastening bolts 39 whereby the plates, after adjustment, can be held securely to the heads of the sizing forms. The plates are to be so adjusted that the distance from their lower edges to the lower surface of the form head 35 shall be 80 equal to the thickness of the sized brick. It is also designed that the parts be so adjusted that, when the cross head 19 reaches the lower limit of its movement, the lower edges of the end plates 37 will be in a plane where 85 they will lightly touch or be in very close proximity to the top surface of the blade 11 and the slide 5 during the shearing operation hereinafter explained. This adjustment of the cross head is effected by raising and lowering the switches 25 through adjustment 90 of the guide plates 22.

Arranged between the frame members 1 beyond the end of the table B are rails 40 yieldingly supported by springs 41. Various constructions and arrangements of 100 springs or the like may be employed for supporting these rails yieldingly. One of these means has been illustrated in detail in Figure 6 wherein the lower portion of the spring 41 is seated in a recess 42 extending into one end of an adjusting screw 43. This screw is carried by an angular bracket 44 attached to the frame member 1 thereabove and a lock nut 45 may be employed for holding the screw in any position to which it may be 105 adjusted.

The inner or exposed side of each rail 40 is formed with a longitudinal groove 46 and mounted to slide in these grooves are flanges 110 extending laterally as at 47 from a carriage 48 mounted for reciprocation between the rails. The top surface of this carriage is in line with the top surface of the slide 5 and formed on the carriage are upstanding parallel partitions 49 spaced apart distances 115 equal to the widths of the respective forms so as to provide separate recesses 50 for the reception of the blocks of bulk material to be sized. Extending transversely of the carriage is a cross strip 51 disposed at an angle 120 to the top surface of the carriage as shown particularly in Figures 7 and 8. This cross strip, which constitutes a deflector, can be adjusted along the carriage toward and from the partitions 49. For this purpose brackets 125 130

52 may be employed, these brackets having bolts 53 which slide in slots 54 formed in the carriage but which can be tightened to hold the deflecting strip 51 against movement.

5 Adjacent each side of the carriage 48 is a coupling block 55. Each of these blocks has a longitudinal rib 56 extending laterally therefrom adapted to be seated slidably within one of the grooves 4. A pin 57 extends transversely of and inwardly from each end portion of each coupling block 55 and these pins have depending fingers 58 extending loosely through apertures 59 in the side portions of the carriage 48. Thus it 10 will be seen that the carriage has a limited up and down movement relative to the coupling blocks 55 but the blocks will necessarily move with the carriage when the same is reciprocated.

20 Formed in the upper face of each coupling block is a recess 60 designed, at certain times during the operation of the mechanism, to receive the head 13 of one of the latches 12. That end of each block 55 nearest the slide 5 is cut away so as to leave an inclined lug 61 for engagement by the head 13 of the latch 12, said lug forming one wall of the recess 60.

Standards 62, which can be in the form of 30 threaded posts, are extended upwardly from plates 63 lapping the sides of the frame members 1. Each of these plates is slotted longitudinally as at 64 to receive a clamping bolt 65. A cross rod 66 is extended across 35 the machine above the path of the slide 5 and above the table B, this rod being provided at each end with a collar 67 mounted on a post 62 and connected adjustably there to by nuts 68. The rod may be mounted for 40 rotation in the end sleeves 67 in which event a gate 69 which depends from the rod may be made integral therewith. This gate constitutes means for preventing sized bricks from moving in one direction with the slide 45 5 and, to insure such action, stops 70 are extended from the sleeves 67 to constitute abutments for the gate and limit its swinging movement toward the carriage 48. The gate is free to swing away from the carriage, 50 however, as when the sized material is pressed thereagainst. Instead of mounting a stripping gate as described and as shown in detail in Figure 5, said gate, as shown at 71 in Figure 11, may be mounted on arms 72 55 fixedly connected to and movable with the cross head 19. When mounted in this manner the gate can be adjusted vertically either by providing a vertically adjustable bolt and slot connection between each arm 72 and the cross head 19 or between each arm 72 and the gate 71. Such a construction is so obvious that detailed illustration thereof is not deemed necessary.

Under normal conditions the carriage 48 60 is located close to the outlet end of the chute

3, cross head 19 is elevated with the pins 32 positioned as in Figure 2 and the slide 5 beneath cross head 19. These positions have been illustrated in Figure 7. Assuming that the parts have been adjusted to produce 70 bricks of a predetermined size, the attendant standing beside the machine sees that portions of bulk material leaving the chute 3 are positioned within the respective recesses 50 against the deflecting strip 51. It 75 is of course essential that the bulk material placed in each recess be oversize. Following this operation the movement of the press mechanism will cause the pitmen 8 to pull on the strips 6. This will cause slide 5 to 80 move along the table B from the position shown in Figure 7 to the position shown in Figure 8. At the same time the switches 25 will likewise be moved from the position shown in Figure 7 to the position shown in 85 Figure 8. As the latches 12 are in engagement with the coupling blocks 55, the carriage 48 with the bulk material thereon will travel with the slide 5 until it arrives directly beneath the sizing forms made up of 90 the heads 35 and plates 37. At this time the deflecting strip 51 will extend slightly beneath one end of the sizing forms. As soon as the carriage 48 reaches this position the fingers 14 ride onto the lifting cams 15 95 which move the heads 13 out of the recesses 60 so that movement of the slide 5 can continue while the carriage 48 will remain under the cross head 19. At this time the pins 32 are seated in the extension slots 28, it being understood that as the pins 32 move toward this slot they will depress the points 31 of switch tongues 30, said points thereafter shifting back to their normal positions as in Figure 8. Following the completion 100 of this operation the slide 5 begins its return movement, the switches 25 travelling therewith. This will result in the inclined ends of the tongues 30 coming against the pins 32 and forcing them downwardly. Consequently the cross head 19 will move 105 downwardly against the action of the springs 20 and the sizing forms will come against and compress the bulk material in the recesses 50. This bulk material will completely fill the spaces defined by the sizing forms and the partitions 49 and as the downward movement of the cross head and sizing forms is just sufficient to bring the lower edges of the plates 37 to the plane of the 110 top of slide 5 it will be apparent that should there be any surplus bulk material, the same will exude under the plates 37 and at the same time press the carriage 48 downwardly 115 against the action of its sustaining springs 41. Immediately following this action and while the cross head is being held in lowered position by the switch tongues 30, the latch heads 13 ride over the lugs 61 and snap into 120 the recesses 60 after which the strips 6 come 125 130

against the blocks 55 and push them longitudinally. Thus the carriage 48 will be withdrawn from under the material filling the sizing forms and during this withdrawal 6 of the carriage to the position shown in Figure 7 the blade 11 will shear off the surplus bulk material while the slide 15 will come to position under the sized bricks and support them. As soon as the slide 5 completes 10 its movement to position under the sized bricks, the pins 32 will move past the adjacent ends of the switch tongues 30 whereupon the springs 20, being released, will elevate the cross head 19 and causing the sizing forms 15 to lift out of engagement with the sized bricks.

The operation thus far described is then 20 repeated but it will be seen that as the slide 5 moves away from the position shown in Figures 7 and 9 the sized bricks S will travel therewith and come against the gate 69 which will swing out of the path thereof until the bricks pass the gate whereupon 25 said gate will swing back to normal position.

25 It might be added that during the next succeeding operation while the slide 5 is moving toward the path of the cross head 19 the sized bricks will be held against movement so that slide 5 will be withdrawn from 30 the bricks S as they are held as shown by broken lines in Figure 9. This position of the bricks will be maintained until the slide is completely withdrawn from under them whereupon the bricks will drop onto the 35 table B into the path of the abutment 10. Obviously, therefore, when the slide 5 again moves toward the press A the bricks S will be pushed in the path thereof into the press. In other words, during each movement of 40 the slide 5 toward the press bulk material is being carried to position under the sizing forms, sized bricks are being conveyed against and past the stripping gate, and another group of sized bricks are being pushed 45 by the slide to the press.

What is claimed is:

1. A brick sizing machine including a sizing form, a yieldingly supported carriage, means for actuating the carriage to position 50 bulk material in the path of the sizing form, means for actuating the sizing form to compress the bulk material on the carriage, thereby to depress the carriage and express surplus bulk material between the carriage and the form, and means for severing the expressed bulk material from the material within the form.

2. A brick sizing machine including a sizing form, a yieldingly supported carriage 60 for supporting bulk material in the path of the form, means for actuating the sizing form to compress the bulk material on the carriage and express surplus bulk material between the form and carriage, and means 65 operating in timed relation with the sizing

form for withdrawing the carriage from under the bulk material, severing the surplus material from the contents of the sizing form, and positioning a supporting means beneath the material in the sizing form. 70

3. A brick sizing machine including a sizing form, means for intermittently raising and lowering the form, a carriage for positioning bulk material in the path of the form while raised, means for supporting the carriage for yielding movement under the pressure of surplus bulk material during the movement of the sizing form toward the carriage, means for successively withdrawing the carriage from the bulk material and 75 severing the surplus bulk material while the form is in its lowered position, said severing means including means for supporting the sized bulk material following the raising of the form and conveying the sized 80 material from under the form. 85

4. A brick sizing machine including a sizing form, means for intermittently raising and lowering the form, a yieldingly supported carriage for positioning bulk material in the path of the form while raised, a slide, cut off means movable therewith substantially in the plane of the lower edges of the sizing form, means actuated by the movement of the slide in one direction for lowering the form to compress bulk material upon the carriage and express surplus material below the edges of the form, and thereafter release the form for upward movement, and means operated by said 90 movement of the slide for shifting the carriage from under the bulk material prior to the raising of the form, said cut off means being movable with the slide during such movement to remove surplus bulk material, 95 said slide constituting a support and carrier for the bulk material subsequent to the removal of the surplus and to the elevation of the form. 100

5. A brick sizing machine including a sizing form, yielding means for holding the same normally elevated, a carriage yieldingly supported and movable into and out of position in the path of the form for supporting bulk material, a slide, means operated by the movement of the slide in one direction for shifting the sizing form to compress bulk material upon the carriage and express surplus material between the carriage and the form, said means operating to release the form upon the completion of the compressing operation for return to normal or raised position, means operated by the slide when moved in the same direction for shifting the carriage from under the compressed material prior to the release of the form, and means movable with the slide during said movement for severing the surplus bulk material prior to the release of the form, said slide constituting a support 110 115 120 125 130

and carrier for the bulk material subsequent to the removal of the surplus and the release of the form.

6. A brick sizing machine including a yieldingly supported carriage, a sizing form for compressing bulk material thereon and expressing surplus material between the form and the carriage by depression of the carriage, and means for severing the surplus material along the plane of the bottom of the form.

7. A brick sizing machine including a yieldingly supported carriage, a sizing form for compressing bulk material thereon and expressing surplus material between the form and the carriage by depression of the carriage, a slide movable to position under the form to support bulk material delivered from the form, and means movable with the slide for severing surplus material along the bottom of the form in advance of the delivery of material from the form to the slide.

8. A brick sizing machine including a yieldingly supported carriage for holding bulk material, a sizing form for compressing the bulk material upon the carriage and expressing surplus material between the form and the carriage, a reciprocating slide movable into and out of position beneath the form to receive and remove bulk material deposited by the form, means actuated by the slide for moving the carriage in advance thereof from engagement with the bulk material, and means movable with the slide and following the carriage for severing surplus bulk material from the form.

9. A brick sizing machine including a yieldingly supported carriage, a slide, means for reciprocating the slide, means actuated by the slide for moving the carriage intermittently backwardly and forwardly, a sizing form, means actuated by the slide for shifting the form when the carriage is in one extreme position thereby to compress bulk material supported by the carriage, means for shifting the form during the movement of the slide to disengage the form from the bulk material and leave said material on the slide, and means carried by the slide for severing surplus material from the form prior to disengagement of the form from the material.

10. A brick sizing machine including a bulk holding carriage, a yieldingly supported cross head, a sizing form carried by the cross head, a switch mounted for reciprocation, a tiltable tongue cooperating with the switch, projecting means on the cross head for sliding engagement with the switch and tongue, a slide, a connection between the slide and switch, and means for shifting said slide to displace the carriage and position the slide beneath the form, said switch and tongue being mounted to travel with the slide during said movement to successively force the

form toward the carriage and release the cross head.

11. A brick sizing machine including a sizing form, a carriage movable into and out of position thereunder, a slide, a shearing blade movable with the slide, means for reciprocating the slide, means controlled by the slide for imparting an up and down movement to the sizing form, a latch movable with the slide, means movable with the carriage for engagement by the latch, and means for automatically disengaging the latch during the movement of the slide and carriage in one direction, thereby to position the carriage in the path of the sizing form during continued movement of the slide.

12. A brick sizing machine including a sizing form mounted for reciprocation, a carriage movable into and out of position in the path of the form, a slide, a shearing blade carried by the slide, means controlled by the slide for reciprocating the sizing form, said slide constituting means for shifting the carriage from under the form and moving the blade across the form while said form is at rest in one extreme position, and cooperating means on the slide and carriage for moving the carriage with the slide and depositing it beneath the form during the movement of the slide while the form is at rest in its other extreme position.

13. In a brick sizing machine a yieldingly supported carriage, a sizing form for compressing bulk material on the carriage to express surplus material between the carriage and the form, a slide having means for shearing the surplus bulk material from the form during the movement of the slide to position beneath the form, means for actuating said slide to displace the carriage from beneath the form, means controlled by the movement of the slide for reciprocating the form in timed relation to the slide thereby to deposit bulk material from the form onto the slide subsequent to the displacement of the carriage, said slide constituting means for withdrawing the bulk material from position beneath the form, and a stripping gate for holding the bulk material against return movement with the slide toward the path of the form.

14. A brick sizing machine including a yieldingly supported carriage, upstanding portions thereon providing a recess for receiving bulk material, a yieldingly supported cross head, a sizing form carried thereby, means for shifting the cross head against the action of its supporting means to direct the form into the recess to compress and size the bulk material therein and express surplus material between the form and carriage.

15. A brick sizing machine including a yieldingly supported carriage, a cross head, yielding means for holding the cross head normally elevated, a sizing form movable

with the cross head, means for shifting the cross head against the action of its yieldable supporting means to compress bulk material between the form and carriage and express surplus material by the depression of the carriage, and means for simultaneously shifting the carriage from the compressed material and severing the surplus material from the form.

16. In a brick sizing machine the combination with a sizing form mounted for recipro-

cation, and a brick press, of a carriage for conveying bulk material into the path of the sizing form, said carriage being yieldably mounted, a slide constituting means for displacing the carriage and receiving the sized bulk material from the form, said slide including means for shearing surplus material from the form. 15

In testimony that I claim the foregoing as 20 my own, I have hereto affixed my signature.

SYLVESTER GOSS HAMER.
